United States Patent Office

Des. 194,688
Patented Feb. 26, 1963

194,688

GOLF BALL OR SIMILAR ARTICLE

Frank Santora, 2301 N. Grant Ave., Wilmington, Del.

Filed June 8, 1960, Ser. No. 60,877

Term of patent 14 years

(Cl. D34—5)

The FIGURE is an elevational view of a golf ball or similar article showing my new design.

The face of the sphere not shown is plain and unornamented.

I claim:

The ornamental design for a golf ball or similar article, substantially as shown and described.
